UNITED STATES PATENT OFFICE.

THOMAS A. LOGAN, JOSEPH F. BROWN, AND CHARLES E. DAVIS, OF KANSAS CITY,
MISSOURI.

FOLDING BED.

1,424,926.

Specification of Letters Patent. Patented Aug. 8, 1922.

Application filed December 2, 1920. Serial No. 427,755.

To all whom it may concern:

Be it known that we, THOMAS A. LOGAN, JOSEPH F. BROWN, and CHARLES E. DAVIS, citizens of the United States, and residents of Kansas City, Jackson County, Missouri, have invented a certain new and useful Improvement in Folding Beds, of which the following is a complete specification.

This invention relates to folding beds of that class in which provision is made for accommodating a full-width mattress, and the primary object is to produce a folding bed of this type which can be moved and opened and closed easily, cannot close accidentally, and in which the mattress and bedding is held firmly against displacement when the bed is closed or being opened. A further object is to produce a folding bed possessing the features of advantage set forth as desirable, which is of attractive appearance and of comparatively inexpensive construction.

With the above mentioned objects in view, the invention consists in certain novel and useful features of construction and combinations of parts as hereinafter described and claimed; and in order that it may be fully understood reference is to be had to the accompanying drawings, in which:—

Figure 1, is a broken vertical section of a folding bed embodying the invention, the section being taken on the line I—I of Figure 2.

Figure 2 is a horizontal section taken on the line II—II of Figure 1.

Figure 3, is a section corresponding to Figure 1, but showing the bed in a partially folded position.

Figure 4, is a section corresponding to Figure 3, but showing the bed in fully closed position.

Referring now to the drawings in detail, where like reference characters identify corresponding parts, 1 indicates a pair of parallel base bars formed or provided at their front ends with upwardly projecting arms and connected together at their rear ends by a head frame 2, said head frame being preferably of greater width than the distance between the said parallel bars. The rigid frame constituted by said bars and said head frame, is mounted upon suitable casters 3 for convenience in rolling the bed in any direction. The side frames, consisting of said bars and their upwardly projecting arms, are rigidly connected together by one

or more cross bars 4, and the upper ends of the said arms are formed with pivot sockets 5, receiving the inwardly-projecting pivot studs 6 rigidly secured to the sides 7 of a rectangular mattress frame, the head and foot bars or rails 8 of said frame being rigidly connected to the ends of the side rails 7 by arms 9. The head and foot rails form supports for the customary wire fabric 10, upon which the mattress and bedding is adapted to rest, it being noted that the fabric 10 occupies a position above the plane of the pivotal point of said rectangular frame, and that said fabric lies between the head frame 2 and the arms of the bars 1, when the bed is closed, as shown by Figure 4, and it will also be noted in this connection, that the supporting arms do not in anywise interfere with the use of a mattress of the same width as the head frame 2, as said mattress when in vertical position is above the base bars 1 and projects beyond or overhangs the same at their outer sides. It will thus be apparent that the frame of the bed need not exceed in width the regulation width mattress in order to accommodate the same, as is usually the case with folding beds of this character.

The foot frame 11 of the bed is pivotally connected by pairs of links 12 and 13 to the side rails 7 of the rectangular mattress frame, and said links are so positioned and proportioned that when the bed is in opened position, the foot frame bears against the foot rail 8 and the links brace said foot frame in vertical position, the said links when the bed is in folded condition, permitting the foot frame to occupy a vertical position adjacent the vertical plane of the side rails of the bed, and said foot frame is mounted upon casters 11^a so that when the bed is opened it may be readily moved upon the floor without necessitating the lifting of the foot frame.

A pair of rocker bars 14 are fulcrumed at 15 to the base bars 1, the head ends of said rocker bars being connected by retractile springs 16 to brackets 17 secured rigidly to the head frame by means of cross braces 2^a thereof or in any other suitable manner. The opposite ends of the rocker bars 14 are connected by retractile springs 18, to a pair of arms 19 rigidly secured to the pivot studs 6 of the mattress-carrying frame. The springs 16 and 18 are under tension which is greatest when the bed is

unfolded and which is gradually diminished as the folding operation occurs. The springs 16 exert sufficient retractive force to support the bed as a whole, in folded condition. The springs 18 exert less force than springs 16, but sufficient to hold the mattress-carrying frame in vertical position, and in the unfolding operation said springs 18, are first tensioned before applying sufficient pull on the rocker levers 14 to effect appreciable stretching of the springs 16. The springs 16 and 18 conjointly as above indicated hold the mattress-carrying frame in vertical position, but to guard against any possibility of accidental unfolding action of the bed, the head rail 8 is provided with a pair of beveled teeth 20 adapted as the mattress-carrying frame swings downward to a horizontal position, to slightly repress a pair of spring arms 21 carried by the head frame, and then clear the ends of said arms, which instantly react and thus occupy a position rearward of said teeth and guard against accidental folding operation, or the tipping of the head frame over upon the bed should pressure be applied forwardly on the head frame or foot frame in moving the bed. The head rail 8 is equipped with a frame 22 to abut against the head end of the mattress when the same is resting upon the fabric 10, and any suitable foot clamps, not shown because in common use, may be provided to clamp the foot-end of the mattress to its supporting frame.

A pillow and mattress clamping frame 23 is pivoted as at 24 to the frame 22, and said frame 23 at one end has an arm 25 pivotally connected by a curved link 26 with a swing arm 27 pivoted to the inner side of the adjacent arm of one of the base bars 1, this method of linking the said parts together permitting the clamp frame 23, when the bed is folded, to swing forwardly and apply pressure upon the pillows, not shown, to clamp the same, the bed covering and the mattress firmly in place, at the same time permitting the head end of the mattress-carrying frame to swing downwardly between the head frame and the upwardly projecting arms of the base bars, as shown most clearly in Figure 4. In this connection it will be understood that the clamping movement of the frame 23 occurs because of the relative change of positions between the frame 22 turning around the pivotal point 6, and the links 27 fulcrumed or pivoted eccentrically of said pivotal point 6, and that when the bed is unfolded, the eccentricity of said pivotal points, results in the opening movement of the clamping frame, as will be readily understood by reference to Figures 1, 3 and 4 of the drawings.

65 To unfold the bed, the foot portion is

pulled downward to impart movement in the same direction to the mattress-carrying frame, this movement being easily effected because the resistance of the springs 18 and 16 is successively overcome, that is to say 70 springs 18 yield to the initial part of the movement and the gravitational tendency of said frame assists the operator in overcoming the resistance of the stronger springs 16. In the reverse of closing movement, both sets of springs aid the operator who can therefore close the bed with practically no exertion. It will be apparent that the bed when unfolded can be rolled upon the floor and that likewise when folded it can 75 be readily rolled to any desired point. With beds of this character it is frequently desirable to dispose them in a closet when not in use, and it has been found desirable to provide guiding means whereby they can 80 be readily placed or rolled into such a closet without danger of being scratched or of striking the woodwork and marring the same. To accomplish this, a hook 28 is secured to the head frame and slidingly engages a suitably-supported guide rail 29, adapted to extend from a point within such closet to one of the stiles of the closet doorway. As it is not new to dispose beds in closets during the day, the drawings 85 (Figure 1), only show the slidable interlocking relation between the rail and the hook. 90

From the above description it will be apparent that we have produced a folding 100 bed embodying the features of advantage set forth as desirable in the statement of the object of the invention, it being understood that we reserve the right to make all changes within the scope of the appended 105 claims.

We claim:

1. In a folding bed, a rectangular frame comprising a transverse headframe and a pair of side bars projecting forwardly from the headframe adjacent the lower corners thereof and terminating at their front ends in upwardly projecting arms, a rectangular frame for carrying a mattress, pivoted at an intermediate point of its sides, to said arms and of substantially the same width as the headframe, a pair of curved arms rigidly secured to the rectangular frame at its pivotal point, a pair of relatively U-shaped rocker bars pivoted to said side bars, a pair of retractile springs connecting the rear ends of said rocker bars to the headframe, and a second pair of retractile springs connecting the front ends of said rocker bars to said pair of curved arms. 110

2. In a folding bed, a rigid framework comprising a transverse headframe and a pair of side bars projecting forwardly from the headframe adjacent the lower corners thereof and terminating at their front ends 115

- in upwardly projecting arms, a mattress-supporting frame of greater width than the distance between said arms, pivotal supports for said mattress-supporting frame 5 carried at the upper ends of said arms, a rocker arm pivoted to the forwardly projecting side bars, and a pair of retractile spring connected at one of their ends to opposite ends of the rocker bar, the free end 10 of the spring adjacent the headframe being connected thereto, and the free end of the other spring being connected to the mattress-supporting frame.
3. In a folding bed, a rigid framework 15 comprising a transverse headframe and a pair of side bars projecting forwardly from the headframe adjacent the lower corners thereof and terminating at their front ends in upwardly projecting arms, a mattress-supporting frame of greater width than the distance between said arms, pivotal supports for said mattress-supporting frame carried at the upper ends of said arms, a relatively U-shaped rocker arm pivoted substantially centrally of its length to said side 20 bars, and a pair of retractile springs connected at one of their ends to opposite ends of the rocker bar and at their other ends respectively connected to the mattress-supporting frame and the headframe.
4. In a folding bed, a rigid framework 25 comprising a transverse headframe and a pair of side bars projecting forwardly from the headframe adjacent the lower corners thereof and terminating at their front ends in upwardly projecting arms, a mattress- 30 supporting frame of greater width than the distance between said arms, pivotal supports for said mattress-supporting frame carried at the upper ends of said arms, a 35 second pair of arms rigidly secured to said mattress-supporting frame, a rocker arm pivoted to the forwardly projecting side bars, and a pair of retractile springs connected at one of their ends to opposite ends 40 of the rocker bar and at their other ends respectively connected to the second pair of arms carried by the mattress-supporting frame and to the headframe.
5. In a folding bed, a rigid framework 45 comprising a transverse headframe and a pair of side bars projecting forwardly from the headframe adjacent the lower corners thereof and terminating at their front ends in upwardly projecting arms, a mattress-supporting frame of greater width than the distance between said arms, pivot pins rigidly secured to said rectangular frame and journaled for rotation in the upper ends of said arms, a second pair of arms rigidly 50 secured to said pivot pins, a rocker arm pivoted to the forwardly projecting side bars, and a pair of retractile springs connected at one of their ends to opposite ends of the rocker bar and at their other ends respectively 55 connected to the second pair of arms secured to said pivot pins.

In testimony whereof we hereunto affix our signatures.

THOMAS A. LOGAN.
JOSEPH F. BROWN.
CHARLES E. DAVIS.
